UNITED STATES PATENT OFFICE.

THURE DAHL, OF NEW YORK, N. Y., ASSIGNOR TO LIGHTOLIER COMPANY, A CORPORATION OF NEW YORK.

DESIGN FOR A LOOP FOR LIGHTING FIXTURES.

61,011.

Specification for Design.

Patented May 30, 1922.

Application filed December 30, 1920. Serial No. 434,158. Term of patent 3½ years.

To all whom it may concern:

Be it known, that I, THURE DAHL, a subject of the King of Sweden, residing at New York city, in the county of New York and State of New York, have invented a new, original, and ornamental Design for Loops for Lighting Fixtures, of which the following is a specification, reference being had to

the accompanying drawing, forming part thereof.

The figure is a side view of a loop for a lighting fixture showing my new design.

I claim:

The ornamental design for a loop for lighting fixtures as shown.

THURE DAHL.
